UNITED STATES PATENT OFFICE.

CARL GIESECKE, OF BRUNSWICK, GERMANY.

PROCESS OF AGGLOMERATING FLUE-DUST OR OTHER FINELY-DIVIDED MATERIAL.

1,162,600.

Specification of Letters Patent. Patented Nov. 30, 1915.

Application filed May 10, 1915. Serial No. 27,214.

To all whom it may concern:

Be it known that I, CARL GIESECKE, engineer, citizen of the Duchy of Brunswick, Empire of Germany, residing at Brunswick, Germany, have invented certain new and useful Improvements in Processes of Agglomerating Flue-Dust or other Finely-Divided Material, of which the following is a specification.

10 My invention relates to improvements in the process of burning or agglomerating dust from the throats of high furnaces, fine ore, and the like, and the object of the improvements is to provide a process whereby 15 the said materials are baked together or agglomerated.

In the preferred form of the invention the dust or fine ore is moistened a little and charged in a shaft furnace, as is known in 20 the art. In a certain zone of the said shaft furnace the material is subjected to the sudden action of high heat, and immediately after leaving the said zone, it is rapidly cooled by the action of blasts of compressed 25 air. By thus suddenly heating the material it is baked together so as to form lumps of larger or smaller size, and yet the particles are not molten or fused together. By suddenly cooling said lumps inner strains are 30 caused, which burst the big lumps apart, so that the product withdrawn from the furnace is in the form of pieces which are suitable for further treatment. In order to produce the high temperature which is necessary 35 for suddenly heating the material and also to produce the immediately following rapid cooling of the material I supply compressed air to the mixture of fuel and material to be burnt which is passing downward 40 within the furnace, the said compressed air being supplied within an annular zone and from the side through the wall of the furnace and tangentially of the inner part of the furnace. By thus supplying the 45 compressed air, the zone within which high heat is produced is exactly limited at its lower end, so that the material which has been heated is suddenly passed from the hot zone to the cold one in which cooling takes 50 place.

A furnace for carrying the invention into effect is illustrated in the accompanying drawing wherein—

Figure 1 is a vertical sectional view, and 55 Fig. 2 is a horizontal sectional view on the line 2—2 of Fig. 1, looking downwardly.

The furnace includes a shaft *b* arranged above a grate portion *g* and surmounted by a cupola *a* having suitable openings (not shown) through which the flue dust or like material, after having been previously moistened, is introduced. The shaft *b* is nearly surrounded by an annular air supply pipe *c* connected to a source of compressed air (not shown) and said pipe is provided with several branch tubes *d* arranged at appropriate intervals throughout its extent and by which it is connected to the shaft *b*, the tubes *d* opening to the interior of said shaft and being disposed tangentially to an imaginary circle within and concentric to said shaft.

The streams of compressed air are directed by the tubes *d* into a cooling zone or plane from which the air rises to the upper 75 burning stratum *e* of the material which is being treated; and in consequence of the compressed air thus introduced into the stratum *e*, the material of said stratum is subject to an extremely high degree of heat. 80 On the other hand, the material of the next lower stratum *f* is, by virtue of the compressed air, substantially cooled and a further cooling of the material takes place in the grate *g*. Inasmuch as the material descends through the furnace in a uniform current and at a measurably fair speed, the material which, while it forms the stratum *e* is greatly heated, is immediately thereafter, 85 as it descends and forms the stratum *f* subjected to the cooling influence of the compressed air in the cooling zone or plane referred to. From this, it follows that the material is first highly heated and immediately thereafter is substantially cooled, the 90 compressed air from the tubes *d* participating in both the heating and the immediately subsequent cooling of the material.

The remaining features of the furnace are of secondary importance.

The grate *g* is of suitable construction to provide for the further cooling of the material and for its descent through the furnace as above explained. Suitable feeding or emptying devices *h* are arranged below 105 the grate to insure of the uniform downward movement of the material through the furnace. The products of combustion escape through a ventilator *i*.

I claim herein as my invention:

1. The herein-described process of agglomerating flue dust or other finely di-

vided material which consists in moistening the said material, charging the same together with fuel in a shaft furnace and introducing compressed air into said material in an annular zone, whereby a stratum of the material is subjected to high heat and is immediately thereafter rapidly cooled.

2. The herein described process of burning or agglomerating materials such as dust from the throats of high furnaces or fine ore, which consists in moistening the said materials, charging the same together with fuel in a shaft furnace, and suddenly sub-

jecting the same to high heat and rapidly cooling the same prior to their discharge 15 from the shaft furnace by supplying there-to compressed air in a direction tangentially of the inner part of the furnace.

In testimony whereof I have hereunto set my hand in presence of two subscribing witnesses.

CARL GIESECKE.
